UNITED STATES PATENT OFFICE.

SAMUEL NORRISH, OF WYOMING, OHIO.

COMBINATION-TOOL.

1,289,524.

Specification of Letters Patent. Patented Dec. 31, 1918.

Application filed January 4, 1918. Serial No. 210,313.

To all whom it may concern.

Be it known that I, SAMUEL NORRISH, a citizen of the United States, residing at Wyoming, in the county of Hamilton and State of Ohio, have invented certain new and useful Improvements in Combination-Tools, of which the following is a specification.

This invention relates to combination tools, and aims primarily to provide a tool which embodies a claw nail puller, a puller for nails having no heads, a wire stretcher, a wire cutter, and a chisel.

A further object of the invention is to provide an instrument of the character mentioned which shall be of extremely simple and inexpensive construction, which may be manufactured at low cost, which has but few simple and readily assembled parts, the said parts being constructed and arranged in such manner as to minimize the opportunity for wear, breakage or derangement, which is capable of being easily and quickly operated, and which will prove thoroughly practical and efficient in use.

With these objects in view, together with others which will appear as the description proceeds, the invention resides in the novel construction, combination and arrangement of parts, all as will be described more fully hereinafter, illustrated in the drawings and particularly pointed out in the claim.

In the drawings:

Figure 1 is a side elevation of a combination tool constructed in accordance with the invention,

Fig. 2 is an edge view of the improved tool, and

Fig. 3 is a fragmentary elevation of one portion of the tool and illustrating the implement for removing nails without heads.

Referring now, more particularly to the drawing, 4 indicates the shank of the improved tool, the said shank being of any approved size and being formed preferably of strong metal. This shank is provided at one end with a head 5, the ends of the head being reduced or tapered as shown, and one of the said ends is cut away as at 6 to provide a V-notch constituting a claw for use in removing nails from planks, buildings, boxes, etc. It will be observed that the outer portion of the head 5 is rounded from one end to the other, to permit of the said head

being rocked during the nail extracting operation.

The opposite end of the head is provided with improved means for facilitating the removal of nails having no heads, and to this end, the said head portion is provided with a yoke member 7, the arms of which straddle the said head end and are pivotally secured to the latter. As shown in Fig. 3 of the drawing, the sides of the head end are reduced so as to receive the yoke arms, and the bight portion of the yoke passes over the extremity of the head and in close proximity thereto. The yoke arms are pivoted to the head as at 8. It will be observed from Fig. 1 of the drawings that the extremity of the head is tapered to a point, and it is obvious that when the point or edge is engaged with the side of a nail and the yoke 7 is swung downwardly over the same, rearward rocking movement delivered to the tool will cause the sharpened edge to bite into the nail and to be held firmly engaged with the latter by the swinging yoke member 7.

The head 5 is provided upon one side and intermediate the ends thereof with an outwardly extending boss 9, the operative surface of which is rounded from one end to the other thereof. A rocking clamp member 10 is pivoted as at 11 to the side of the head adjacent the boss, and is adapted to clamp between itself and the boss the wire which it may be desired to stretch. The rocking clamp member is provided with a rearwardly extending arm 12, carrying at its outer end an inwardly projecting pin or stud 13 engaging in a slot 14 in a lever 15 pivoted as at 16 to the tool head beneath the clamping member 10. The outer extremity of the lever 15 is provided with a pin or detent 17 adapted to engage in a suitable notch or recess in the adjacent surface of the tool shank, this construction enabling the lever to be held firmly to the tool shank when not in use. It is obvious that by the arrangement of the clamp member arm 12 and the rocking lever 15, powerful clamping action in the member 10 may be developed by rocking the said lever.

The lever 15 is provided adjacent its pivoted end with a laterally projecting cutter lug 18, which is adapted when the lever is rocked to pass across a notch 19 in one edge

of the tool shank 4. This particular arrangement provides a wire cutting device, and it will be understood that the wire to be severed will be passed through the notch 5 when the cutting lug is removed therefrom.

The end of the shank 4 opposite to the head 5 is tapered as shown, and is provided with a sharpened bevel edge 20, thus providing a chisel which may be used for various purposes.

From the foregoing it is obvious that I have provided a tool which is of extremely simple construction and which may be readily operated to perform the various functions for which it is designed. It will be understood that the implement rests upon its head 5 with wire clamped in the clamping means thereof when it is desired that the tool be used as a stretcher, and by grasping the shank and rocking the same upon the rounded head, the desired drawing power will be developed. The manner in which the other implements are to be used is obvious.

While the above is a description of the preferred embodiment of the invention it is obvious that the invention is not limited to the precise construction set forth, and minor changes in the details of construction may be resorted to without departing from the invention as defined by the claim.

I claim:—

In a tool of the class described, a head, a boss on said head, a clamping member pivoted adjacent said boss, an arm projecting rearwardly from said member, a lever pivoted at one end to said head between the latter and the said arm, the said lever being provided with an elongated slot, a pin projecting from said arm and into said slot, and means for locking said lever against swinging movement.

In testimony whereof I affix my signature in presence of two witnesses.

SAMUEL NORRISH.
